(57) **CLAIM**

The ornamental design for a lug hammer with opposing keys between fixed shaft and rotatable housing having detachable handles, as shown and described herein.

DESCRIPTION

FIG. 1 is a perspective view of the invention with three handles and a socket poised for attachment thereto, each being needed for most effective use of the invention, the socket being illustrated in broken lines to indicate that it is no part of the design to be patented.

FIG. 2 is a rear end view of the invention with handles attached.

FIG. 3 is a rear end view of the invention with handles attached and an end plate ready for attachment to the rear end of the rotatable housing.

FIG. 4 is a front end view of the invention with handles attached.

FIG. 5 is a top view of the shaft of the invention.

FIG. 6 is a bottom view of the shaft of the invention.

FIG. 7 is a right side view of the shaft of the invention.

FIG. 8 is a left side view of the shaft of the invention; and,

FIG. 9 is a top view of the small rod used for handle attachment and removal.

The elements have been shown separately in FIGS. 1-9 for ease of illustration only.
